UNITED STATES PATENT OFFICE.

LEO STEIN AND CLAYTON F. WETMORE, OF HOBOKEN, NEW JERSEY, ASSIGNORS TO THE NATIONAL CASKET COMPANY, OF SAME PLACE.

DESIGN FOR A CASKET-BODY.

SPECIFICATION forming part of Design No. 28,835, dated June 7, 1898.

Application filed February 28, 1898. Serial No. 672,097. Term of patent 14 years.

To all whom it may concern:

Be it known that we, LEO STEIN and CLAYTON F. WETMORE, citizens of the United States, residing at Hoboken, county of Hudson, and State of New Jersey, have invented and produced a new and original Design for Caskets and the Like, of which the following is a specification.

Our invention relates to designs in caskets, having for its leading characteristic feature the ornamental corner post or molding therefor, which goes to make up the configuration of the casket as a whole.

It consists of the corner molding or post so disposed upon the scarfed corners of the end of the casket-body as to produce a pleasing effect upon the eye, all of which is illustrated in the accompanying drawing, in which we show a casket provided with our new and novel corner.

The design consists in a casket-body having scarfed corners and a corner-molding applied vertically to the casket-body, the said molding consisting of the segment of a cylinder having a double ogee outer surface. 25

a is the body of the casket, having the scarfed corners *b*, and *c* are the corner moldings or posts.

Having described our invention, what we claim, and desire to secure by Letters Patent, 30 is—

The design for a casket-body substantially as herein described and shown.

Signed by us at Hoboken, State of New Jersey, this 16th day of February, 1898.

LEO STEIN.

CLAYTON F. WETMORE.
